UNITED STATES PATENT OFFICE

KATE CONDON, OF CHICAGO, ILLINOIS

DYING PROCESS

No Drawing. Application filed November 2, 1928. Serial No. 316,880.

Ordinarily it is necessary to remove carpets and rugs from the floor or the upholstery from furniture in order to dye it or renovate its color. It is often desirable to renovate rugs, carpets and upholstery in position, but difficulty has always been experienced in applying the color to these materials when treated in this condition. Usually the carpets or upholstery will appear streaked and unevenly colored after the dyeing process and also there is a marked tendency for the color to wear away and leave the material in its original shabby condition.

The object of this invention is to provide an improved process of dyeing rugs, carpets and upholstery in situ.

Another object of this invention is to provide an improved dyeing process which will renovate or restore the color of interior coverings.

A further object of this invention is to provide a process of dyeing carpets and upholstery which will be simple in operation and which may readily be carried out by the housewife.

In the dyeing or restoring of carpets, rugs and upholstery it has been found desirable to wet thoroughly the material which is to be dyed or restored before the dye is applied. The material should not be soaking wet, but it should be wet sufficiently so that a dye solution will spread uniformly therethrough upon application. In the preferred procedure the dye solution is made of substantially greater concentration than the concentration in which it is to be utilized. This concentration is so regulated that the dye solution will be diluted to a desirable extent upon mixture with the moisture or water contained in the carpet, rug or upholstery. It is also desirable to have a small amount of a soapy material in the water utilized as a dampening or wetting agent for the material to be dyed.

A specific example of the application of this process to the dyeing of a rug will be given, but it is to be understood that the invention is not restricted to the particular steps as set forth or to dyeing the particular material described. The carpet is first wet well with warm water, which should not be too

hot, and then soap is thoroughly scrubbed into it with a brush. After the soap has penetrated through the material, the larger part of it, especially that upon the surface of the material, is removed by rubbing the material with a cloth dampened with warm water by a scraper or a squeegee with a soft rubber contact surface which will not injure the nap. When certain materials are treated in this manner, it may also be desirable to rub the surface with a dry cloth to restore the nap at this point. The dye solution is then applied to the material before any substantial drying takes place. Sufficient water should have been added to the rug so that it will now be thoroughly moistened without being soaking wet. It should be possible to squeeze small quantities of water from it with pressure.

A dye soluble in cold water is preferably used. Either an acid or a basic dye may be used and the dye is preferably used in proportion of about one teaspoonful of dye to between one-half to two quarts of water. The dye should preferably never be used in larger quantities than about four teaspoonfuls to one quart of water and not in smaller quantities than about one-fourth of a teaspoonful to one quart of water. Acid dyes should preferably be used in greater dilution than basic dyes. The concentration of the dye solution will vary both with the character of the dye, the material which is being dyed and the shade which it is desired to produce. The dye may be applied with a soft brush and should be allowed to spread evenly and uniformly through the dampened material. When the dye has been applied, the material may be allowed to dry partially for about one-half hour to one hour and then the surface of the material is rubbed with a damp sponge or cloth to remove any excess dye upon the nap of the material.

After the sponging operation the rug may be dried with warm air. Fans may be utilized for this purpose, but in this case, the temperature of the drying air should be kept below 110 degrees Fahrenheit to prevent spotting or uneven drying of the coloring material.

I claim:—

1. A process of dyeing interior coverings which comprises thoroughly saturating the material with water containing a small amount of soap, applying a dye solution thereto of greater concentration than desired, regulating the amount of moisture in the covering so that the dye solution will be diluted to the desired extent, and finally drying the material.
2. A method of renovating and restoring the color of interior coverings which comprises saturating the material with warm water, scrubbing a soapy material into the covering until it becomes thoroughly saturated therewith, removing a large part of the soapy material by means of successively rubbing the material with a dampened cloth or sponge, applying the dye solution in greater concentration than the concentration at which it is to be utilized after having regulated the moisture content of the covering so that it will dilute the dye solution to desired extent, partly drying the material from one-half hour to one hour, rubbing the surface of the material with a damp cloth or sponge to remove any excess dye, and finally drying the material.
3. A method of dyeing interior coverings which comprises saturating the covering with moisture without making it soaking wet, regulating the moisture therein so that it will be sufficient to dilute a dye solution to the desired extent, applying a dye solution in greater concentration than that in which it is to be utilized, and then allowing the material to dry.
4. A method of dyeing interior coverings which comprises saturating the covering with moisture without making it soaking wet, regulating the moisture therein so that it will be sufficient to dilute the dye solution to the desired extent, and applying a dye solution in the concentration of one teaspoonful of dye to between one-half to two quarts of water.
5. A method of dyeing interior coverings which comprises saturating the covering with moisture without making it soaking wet, regulating the moisture therein so that it will be sufficient to dilute the dye solution to the desired extent, applying a dye solution in the concentration of between one-fourth to four teaspoonfuls of the dye to one quart of water.
6. A process of dyeing interior coverings which comprises thoroughly saturating the material with water, applying a dye solution thereto of greater concentration than desired, regulating the amount of moisture in the covering so that the dye solution will be diluted to the desired extent, and finally drying the material.
7. A method of renovating and restoring the color of interior coverings which com-

prises saturating the material with warm water, scrubbing a soapy material into the covering until it becomes thoroughly saturated therewith, removing a large part of the soapy material by means of successively rubbing the material with a dampened cloth or sponge, applying the dye solution in greater concentration than the concentration at which it is to be utilized after having regulated the moisture content of the covering so that it will dilute the dye solution to desired extent, partly drying the material from one-half hour to one hour, rubbing the surface of the material with a damp cloth or sponge to remove any excess dye, and finally drying the material.

In testimony whereof I have hereunto subscribed my name Oct. 31, 1928.

KATE CONDON.
